UNITED STATES PATENT OFFICE.

CHARLES R. GIBSON, OF CINCINNATI, OHIO, ASSIGNOR OF ONE-HALF TO WILLIAM H. BRUNING, OF EVANSVILLE, INDIANA.

STEAM ENGINE.

Application filed May 28, 1921. Serial No. 473,485.

To all whom it may concern:

Be it known that I, CHARLES R. GIBSON, a citizen of the United States, and a resident of Cincinnati, in the county of Hamilton and State of Ohio, have invented a new and Improved Steam Engine, of which the following is a description.

My invention relates to steam engines employing sliding valve means and it has for 10 its general object to provide an auxiliary cut-off valve.

Other objects of the invention are to provide for the operation of the auxiliary valves by means controlled by the movements of 15 the cross head.

A further object of the invention is to provide trip means for the cut-off valves adjustable to vary the tripping action and to provide manually controlled means to 20 throw the tripping means into or out of action at will.

The above and other objects as will appear are attained by the cut-off valves and their operating and controlling means here- 25 inafter particularly described.

Reference is to be had to the accompanying drawings forming a part of this specification, it being understood that the drawings are merely illustrative of one example 30 of the invention.

Figure 1 is a side elevation of an engine equipped with my invention;

Figure 2 is a partly sectional plan view with the cut-off valves out of action;

Figure 3 is a view of a portion of the opposite side of the engine at the cross head and slide thereof;

Figure 4 is a detail in enlarged vertical section as indicated by the line 4—4, Figure 40 2;

Figure 5 is a fragmentary sectional plan view of the cylinder and valve chest showing the cut-off valves in action;

Figure 6 is a detail in cross section on the line 6—6, Figure 4;

Figures 7 and 8 are side elevations of elements entering into the trip means for the auxiliary valves.

Figure 9 is a view partly in section and partly in elevation, the view being given to show the valves in elevation.

In the illustrated example, the numeral 10 indicates the base of the engine; 11, the steam cylinder; 12, the valve chest; 13, the 55 piston rod; 14, the cross head; 15, its slide;

15^a, the engine frame adjacent to the slide; 16, the connecting rod; and 17, the crank pin for said rod on the engine shaft 18. The above-mentioned elements may be of any approved form as may also be the valve 60 operating rod 19, here shown as associated with a known valve motion the lever 22 of which has a stud 122 engaged by the "gab" element 23 of the motion for actuating the stem 21 of ordinary valves 20. The numeral 65 24 indicates the reversing lever of the valve motion.

In accordance with my invention I provide cut-off valves 25, 25^a auxiliary to the slide valves 20, said valves 25, 25^a being in 70 the same plane as the main valve to operate over the same valve seat surface and the same live steam ports. The valves 25, 25^a are on the heads 26, 26^a secured to the stems 27, 27^a of the respective 75 cut-off valves 25, 25^a. One stem, 27^a, is adapted to be tripped directly while the other stem 27 is adapted to be tripped by means associated therewith said means in the illustrated example being as follows: 80 An arm 29 is rigid with said stem 27 and with a rod 30 ranging longitudinally of the engine and slidable in bearings 31, 32 thereon. The rear end 30^a of the rod 30 is offset upwardly and is provided with a member 33 85 thereon adapted to be tripped, said member being adjustable by a set screw 34. The stem 27^a of the other auxiliary valve 25^a is provided with a similar member 33^a adapted to be tripped and adjustably secured by a 90 set screw 34^a.

I provide tripping means in association with the cross head 14 consisting of plate-like elements 35 secured to plates 36 pivotally secured to a lateral pin 37 extending 95 from the inner side of the cross head 14. The plates 36 have lateral pins 38 thereon adapted to slide on the upper edge of plate 39 or equivalent frame member presenting a straight top edge. The plate 39 has trans- 100 verse slots 40 through which the elements 33 and 33^a to be tripped extend into the path of the tripping members 35. Each carrying plate 36 has a longitudinal slot 41^a and a screw 41 projects through the trip element 105 35 into the slot 41^a of the adjacent carrying plate. Thus, the screws 41 may be loosened and the trip elements 35 caused to project more or less beyond the ends of the plates 36 for timing the tripping action as desired 110

by engagement of the trips 35 with the elements 33, 33^a on the respective stems 27, 27^a on the auxiliary valves 25, 25^a. Also, the tripping elements 35 are formed each with a slot 43 and a guide pin 42 projects from each carrying plate 36 into said slots 43 to guide the movement of the tripping element 35 to be adjusted and to prevent their turning on the adjusting screws 41. In order to release the tripping element 35 from the elements 33 after tripping action upon a movement of the tripping element in either direction, I provide cam surfaces 44 on the plates 39 adapted to be engaged by the screws 41 so that after a predetermined movement of an element 33 by the tripping element 35, the adjacent screw 41 will ride upwardly on the cam surface 44, thereby causing the tripping element 35 and its carrying arm 36 to swing upwardly with the pin 37 as an axis. In the continued movement of the tripping element 35 in response to a stroke of the cross head 14, the screw 41 will ride along a raised surface 45 on plate 39. In order to accurately adjust the trips 35 to coordinate the tripping action thereof with the movements of the cross head 14 and the main piston, I provide a scale 46 on the slide 15 or on said slide and the adjacent frame part 15^a, a pointer 47 or equivalent indicating mark or device being produced on the cross head 14 at the center. Thus, the indicating means 46, 47 permits of the trips being adjusted according to a given position of the piston to accurately time the tripping of the cut-off valves 25, 25^a with the piston strokes.

For the purpose of optionally throwing the tripping elements 35 out of action, I provide a displacing element preferably in the form of a lift plate 48 lying against the plate 39 and movable vertically to dispose the upper edge of the lift plate below the upper straight edge of the plates 39 or to give an upward movement to the lift plate 48 so that its upper edge will engage the pins 38 on the plates 36 and swing said plates with the tripping elements 35 upwardly about the axis of the pin 37 so that in the reciprocating of the trips by the pin 37, moving with the cross head 14 the trip 35 will be above the planes of the elements 33 on the valve stems. Said lift plate 48 preferably is pivotally connected as at 49 with one arm of a bellcrank lever 50 fulcrumed by a pin 51 which extends through a vertical slot 52 in the plate 48 to allow clearance for the latter in its up and down movements.

In operation, the valves 25, 25^a are moved toward the valve 20 by the movement imparted to the valve rods 27, 27^a, and said valves 25, 25^a are restored to their original positions toward the ends of the valve chest by the movements of said

valve 20. The movements imparted to the valve rods 27, 27^a are regulated and determined by the adjustment of the plate-like elements 35 on the plates 36 through the medium of the slots 41^a and screws 41, said elements 35 projecting more or less beyond the plate 36 or to be positioned within the planes of the ends of said plate 36, thereby determining the engagement of the trip elements 35 with the elements 33, 33^a as previously described. It will be seen from the plan view, Figure 2, and from Figure 4 that the elements 33, 33^a are directly in the path of movement of the elements 35 to be tripped by the latter. In the operation of the valve the described means referred to above for determining the engagement of the trip members result in no jamming of the main valve against the auxiliary valve while it is being positively moved by plate 35. The trip means move the valve 25 or 25^a to a certain point determined by the adjustment and then release it, the auxiliary valve remaining stationary at that point until later when it is struck by the main slide 90 valve and moved back.

I would state in conclusion that while the illustrated example constitutes a practical embodiment of my invention, I do not limit myself strictly to the exact details herein illustrated, since manifestly the same can be considerably varied without departure from the spirit of the invention as defined in the appended claims.

Having thus described my invention, I claim:

1. In an engine of the class described, sliding valve means, and slideable auxiliary cut-off valves operative in one direction by said valve means and actuated in the opposite direction with the movements of the engine cross head.

2. In an engine of the class described, sliding main valve means, auxiliary cut-off valves, and trip means for the cut-off valves operable by the cross head and adjustable to vary the tripping action, the cross head and its slide having correlated indicating means for coordinating the adjustment of the trip means with the movements of the cross head and piston.

3. In an engine of the class described, sliding main valve means, auxiliary cut-off valves, means to cause the cut-off valves to be operated by a reciprocating member of the engine, manually controlled means to throw the trip means out of action, and means for moving the cut-off valves in a direction opposite to the movement given by the trip means.

4. In an engine of the class described, sliding main valve means, cut-off valves having stems, trip means, trip-actuating means operable with the cross head for engaging the stems of the cut-off valves, cams to release

the trip means at the end of each stroke, means for moving the cut-off valves in a direction opposite to the movement given by the trip means, a displacing element for the trip means and adapted to move the latter away from the plane of the cams, and a lever to actuate said displacing element.

5. In an engine, cut-off valves, auxiliary to the main valve means, operating means for the cut-off valve including a trip element, and means associated with the cut-off valves adapted to be engaged by said trip element for actuating the cut-off valves and positioning them for return movement by

the main valve means, a lateral pin on the 15 engine cross head, carrying elements pivotally mounted on said pin, trip members on said carrying elements and adjustable longitudinally to vary the total effective length of the said trip members, cams adjacent to the trip members, members on said trip members adapted to engage said cams at each stroke of the cross head, and means 20 for moving the cut-off valves in a direction opposite to the movement given by the trip members.

CHARLES R. GIBSON.
